J. A. SCROGGINS.
SPRINGLESS DOOR LOCK.
APPLICATION FILED SEPT. 5, 1917.

1,266,332.

Patented May 14, 1918.

UNITED STATES PATENT OFFICE.

JAMES A. SCROGGINS, OF SPRINGFIELD, MISSOURI, ASSIGNOR OF ONE-HALF TO
J. S. LOSEY, OF SPRINGFIELD, MISSOURI.

SPRINGLESS DOOR-LOCK.

1,266,332.

Specification of Letters Patent. Patented May 14, 1918.

Application filed September 5, 1917. Serial No. 189,877.

To all whom it may concern:

Be it known that I, JAMES A. SCROGGINS, a citizen of the United States, residing at Springfield, in the county of Greene and State of Missouri, have invented new and useful Improvements in Springless Door Locks, of which the following is a specification.

This invention relates to improvements in springless door locks and contemplates the provision of a device of this character having a gravity block for operating the bolt to the engaging position, and provided with a simpler and more efficient device for locking the gravity block to hold the bolt in the operative position.

Another object is to provide a gravity operated lock having the handle, the means for manually moving the bolt to the inoperative position, and the means for locking the bolt, so arranged that the bolt may be locked or disengaged as desired without removing the hand from the handle of the lock.

A further object is to so reduce the number of parts and simplify their form and arrangement that the cost of manufacture is reduced and the lock is rendered less liable to get out of order. A form which is considered preferable is shown in the drawings and will be better understood by reference to the description below, the novel features of the invention being recited in the appended claims.

In the drawings:—

Figure 1 is a vertical section, partly fragmentary, showing the lock as applied to a door the escutcheon plate and associated parts being indicated in dotted lines.

Fig. 2 is a vertical section on the line 2—2 of Fig. 1.

Fig. 3 is a fragmentary view showing the method of applying an auxiliary locking device to the bolt.

Fig. 4 is a fragmentary side elevation showing a modified form provided with the conventional knob handle such as used for residences.

Fig. 5 shows end views of various forms of keys for operating the lock.

Referring to the drawings more specifically, the lock has the usual casing 1, which may conveniently comprise a one piece hollow body 2 provided with the side plate 3 detachably secured thereto in any convenient

manner as by screws 4. The front of the 55 casing 1 or that portion adapted to lie flush with the edge of the door, is provided with an opening in a lower portion having slidably inserted therein the usual bolt 5 further supported by guides 6 on the inner walls of 60 the casing. For normally retaining the bolt 5 in the outer position a gravity block 7 has a downwardly extending arm 8 having the end engaged in a notch 9 provided in the upper surface of the bolt 5 and a laterally 65 extending arm 10 having a terminal portion disposed in proximity to an opening 11 provided in the casing. The block 7 is suitably pivoted to the casing at the inter-section of the arms 8 and 10 as by projections 11' on 70 the block engaging recesses 12 in the casing, and it is provided with a web 12' extending between the arms and formed with a transverse notch 13 having the lower adjacent shoulder preferably horizontally disposed. 75 For holding the block in the downward position to restrain the bolt 5 from inward movement I provide a catch or keeper element 14 slidably mounted in a suitable guideway 15 formed in the casing whereby 80 the end of the element 14 is adapted for engagement in and disengagement from the notch 13. An escutcheon plate 16 is provided with a convenient handle 17 and is adapted to be secured to the door adjacent 85 the lock in any convenient manner. The escutcheon plate is formed in proximity to the handle with a pair of openings 18 and 19' respectively, preferably spaced apart vertically over the handle. Slidably mounted 90 in the opening 18 is what may be termed a release stud 19 having a shank extending inwardly through an opening in the casing and terminally connected to the keeper element 14 as by engagement in suitable recesses in the element 14 and provided outwardly of the escutcheon plate with a suitable head for manual actuation. The other opening 19' has pivotally mounted therein a thumb lever 20 extending inwardly 95 through the opening 11 in the casing 1 and terminally engaged under the substantially horizontal arm 10 of the block 7. The outer end of the thumb lever 20 is conveniently disposed over the handle 17 for actuation 100 of the thumb of the operator to move the bolt 5 to the inoperative position.

It will be seen that either the thumb lever

20 or the release stud 19 may be conveniently operated without removing the hand of the operator from the handle.

When desired I may incorporate in the 5 lock the key operated device illustrated in Fig. 3 for securing the bolt, this device consisting of a barrel 21 rotatably mounted in suitable openings 22 in the casing 1 and having an extension 23 adapted to be thrown in 10 and out of the path of the bolt 5 by engagement of a suitable key in either of the central recesses 24 provided in the ends of the barrel 21.

When desired a knob may be used in place 15 of the lever 20 as shown in Fig. 4. In this figure, 23 represents the shank to which a suitable knob is attached. This shank is provided with a tumbler 24 which engages the under face of the arm 10', so that in 20 turning the knob said tumbler will raise the arm 10' to move the bolt 5' inwardly. In this figure I show the bolt 5' provided with a notch 9' for the arm 8' on both of its edges so that the lock may be used on right and 25 left hand doors. As the knob and its connecting parts are well known a detail description is not necessary.

The barrel 21 may be operated by any 30 suitable form of key, such as shown in Fig. 5 and by making the projection 24 of different shapes the lock may be made to be operated by different forms of keys.

It is to be understood that the invention 35 is not limited to the particular form shown and described, and the right is reserved to

variations and departures therefrom falling within the scope of the invention as indicated by the latitude of the claims.

What I claim is:—

1. A door lock comprising a casing, a block consisting of a vertical and horizontal arm, means for pivoting the block to the casing at the junction of said arms, a web connecting the arms together, said web having a recess therein, a manually operated sliding member adapted to engage with said recess to hold the block in locking position, a bolt having a recess therein engaged by said vertical arm, and an operating means 40 engaging with the horizontal arm.

2. The combination with the casing formed with the horizontal guideway, of the bolt block having the horizontal arm, the vertical arm, and the horizontally notched portion between the arms, and pivotally engaged with the casing at the junction of the arms, the keeper element mounted in said guideway for movement in and out of said notch, and the escutcheon plate having the handle, the vertically spaced openings above the handle, the thumb lever pivoted in one of said openings with one end in proximity to the handle and the other end engaged against said horizontal arm, and the release stud extending through the other opening and having the head in proximity to the handle and the shank engaged with said keeper element.

In testimony whereof I affix my signature.

JAMES A. SCROGGINS.
